R. JENKINS.

Lamp.

No. 22,729.

Patented Jan. 25, 1859.

UNITED STATES PATENT OFFICE.

RICHARD JENKINS, OF COVINGTON, KENTUCKY.

LAMP.

Specification of Letters Patent No. 22,729, dated January 25, 1859.

To all whom it may concern:

Be it known that I, RICHARD JENKINS, of Covington, in the county of Kenton and State of Kentucky, have invented a new and 5 useful Improvement in Lamps for Burning Coal-Oil; and I do hereby declare that the following is a full, clear, and exact description of the same, reference being had to the accompanying drawings, forming a part of 10 this specification, in which—

Figure 1, is an outside view of a lamp with my improvement applied to it. Fig. 2, is a top view of the same, and Fig. 3, is a vertical central section.

15 Similar letters of reference, in each of the several figures indicate corresponding parts.

The nature of my invention consists in the employment of an inner and outer cone or 20 semi-sphere in such relation to each other that a space shall exist between them at all parts of their surface, said cones being arranged over the lamp tube so that the inner one is some distance above the same, and being furnished with flame passages, and 25 passages for the introduction of oxygen to the wick tube and to the space existing between the cones or semi-spheres. By thus using two cones, the heavy gases or partially ignited matter rising from coal oil by capillary 30 attraction is confined within a chamber, formed by the two cones a sufficient length of time to allow of a thorough mixing of oxygen therewith so as to insure perfect combustion 35 before said gases rise above the top of the outer cone and give the flame a dull blue appearance at its base. It is not so much the mixing of oxygen or having it impinge upon the heavy or partially vola- 40 tilized gases at the base of the flame that I consider important, but it is the confining of said gases so that perfect combustion will take place before they escape through the upper cone, and thus a perfectly clear flame 45 without any appearance of blue at its base is produced and a complete combustion of the gases of coal oil effected.

To enable others, skilled in the art, to make and use my invention, I will proceed to 50 describe its construction and operation.

A, represents the lamp; B, the wick tube. It is made in two parts, so as to be extended in length and thus serve as a conductor of 55 heat down to the bottom of the lamp where the heavy particles of the oil rest. The wick

of this tube rises and falls by means of a cog pinion C.

D, is the lamp cap. It is screwed on the lamp, as usual.

E, E', are air-chambers of the cap. Air 60 passes into these chambers as indicated by the arrows 1, 1, and circulates about the upper end of the wick tube and thus supports combustion.

F, F', are two cones or semi-spheres of the cap. The cone F, is smaller than that F', and is surrounded by cone F', so that a space G, exists between them at all parts of their surface. In the tops of the cones, oblong slits or flame passages a, a, are provided. 70 The upper passage or slit is made longer than the width of the wick tube, because the flame, in striking the under curved surface of the upper cone is spread so that it perfectly fills the slit or passage. In the sides 75 of the cap, cold air passages b, b, are formed so that the atmosphere shall circulate in the space G, existing between the two cones and thus insure a perfect combustion of the heavier gases before the flame is produced 80 above the upper cone. Air is also admitted above the top of the upper cone by passages c, c, as shown and thus the gases are very perfectly ignited.

I am aware that lamp caps have been so 85 constructed that currents of air are kept circulating about and through the base of the flame, therefore I do not claim this arrangement, but

What I do claim as my invention and desire to secure by Letters Patent, is—

The combination of the inner and outer cones, when arranged in relation to the wick tube and each other, substantially as specified and supplied with air or oxygen for the 95 purpose of maintaining a perfect combustion of the heavier gases or matter rising by capillary attraction in the space or chamber existing between the cones and thus producing with coal oil, a brilliant flame with 100 very little, if any, blue appearance at its base, above the outer cone, substantially as set forth.

The above specification of my improvement in burning coal oil signed by me this 105 ninth day of December 1858.

RICHARD JENKINS.
